UNITED STATES PATENT OFFICE.

NORMAN W. CUMMINS, OF PLYMOUTH, MICHIGAN.

SIDE-CLAMP HOOD FASTENER.

Application filed October 9, 1925. Serial No. 61,510.

In my Patent No. 1,592,257, issued July 13, 1926, there is disclosed a hood fastener located outside of a hood wall and adapted to fasten the hood wall in a closed and clamped position whereby the hood wall cannot become accidentally displaced nor rattle during the operation of an automobile or similar vehicle. The hood fastener includes a wall engaging buffer carried by a pivoted hook shaped member associated with a catch element, and this invention has special reference to the mounting of the buffer or wall clamping member.

The object of this invention is to provide an outside pivoted hood fastener with a yieldable buffer resiliently supported to be clamped against a hood wall, with the buffer arranged so that its clamping action is incident to placing the fastener in engagement with the hood wall. In resiliently supporting the buffer it may adjust itself, under compression, relative to the hood wall, and pressure may be brought to bear against the buffer to insure a positive and reliable holding device for the hood wall.

A further object of this invention is to provide a durable and inexpensive hardware article and the construction entering into the article will be hereinafter described by aid of the drawing, wherein

Figure 1 is a front elevation of the hood fastener;

Fig. 2 is a vertical sectional view of the same, and

Fig. 3 is a plan of the fastener.

The hood fastener comprises a set of ears or lugs 1 connected by a pivot pin 2 and constituting a bearing which is suitably fastened to a fender apron 3 on a sill member or vehicle frame 4, said fender apron having a stop flange or abutment 5 for the lower edge of a hood wall 6 adapted to form part of a hood inclosing the engine or power plant of an automobile or similar vehicle.

Pivotedly mounted on the pin 2 is the lower angular end 7 of a clamping member 8 extending into a cylinder or barrel 9 provided with a catch element 10 having a hook 11 and a grip or handle 12. In the barrel or cylinder 9 is a coiled expansion spring 13, which encircles the member 8 and engages an abutment 14 mounted on the member 8 within the cylinder or barrel. The expansive force of the spring 13 is adapted to hold the cylinder 9 in a retracted position relative

to the clamping member 8 and with the hook 11 in engagement with a suitable keeper 15 attached to the hood wall 6.

Mounted on the angular end 7 of the clamping member 8 is a resilient member or strip 16 having its upper end embedded in the outer portion of a compressible buffer 17 adapted to forcibly engage the hood wall 6 and hold the hood wall against the stop flange 5, as best shown in Fig. 2. The buffer 17 may be conveniently made of rubber or other yieldable material and said buffer may be engaged by the lower portion of the cylinder or barrel 9 so that said buffer, in its compressed state against the wall 6 will be positively held against said wall by engagement of the hook 11 with the keeper 15. In other words, the buffer 17 cannot back away from the hood wall even though it is resiliently supported and the resilient member or strip 16 will permit of the buffer, under compression adjusting itself to the wall 6 and the configuration of the cylinder 9.

Lifting the handle 12 to disengage the hook 11 from the keeper 15 causes the cylinder 9 to shift relative to the buffer 17 and as the cylinder partly or entirely releases the buffer 17, said buffer will momentarily reduce the pressure against the hood wall and by its expansive force tend to force the entire fastener outwardly, whereby it shifts on its pivot after the hook 11 is free of the keeper 15.

The hood fastener affords a side clamping action exteriorly of the hood wall and it is obvious that the fastener may be swung downwardly to permit of the lower edge of the hood wall being readily shifted relative to the stop flange 5, as when opening the hood.

The stop flange 5 constitutes an abutment or means of limiting the closing movement of the hood wall and defining its position, but it is to be understood that this stop flange or member may have for its equivalent the walls of a cowl and radiator adapted to be engaged by the end edges of the hood wall. I do not care to limit my invention to the precise construction or location of the stop member because there are various types of such members in use that will answer my purpose.

This invention is particularly directed to the mounting of the buffer 17 and the manner in which it is braced against the hood wall by the lower end of the cylinder 9.

Obviously such changes may be made in the construction of the hood fastener as fall within the scope of the appended claims.

What I claim is:—

- 5 1. In a hood fastener wherein a hood wall is adapted to be clamped down and against a stop member, and wherein a catch element is placed in hooked engagement with the hood wall to effect such clamping action against the stop member:—supporting means for said catch element; said means comprising a clamping element pivotally mounted adjacent the stop member and yieldingly supporting said catch element, and a buffer resiliently supported by said clamping element and adapted to be compressed between the hood wall and the lower end of the catch element.
- 10 2. A hood fastener as called for in claim 1, wherein said buffer is mounted on the upper end of a resilient member carried by the lower end of said clamping member.
- 15 3. In a hood fastener wherein a hood wall is adapted to be clamped down and against a stop member, a fastening device pivotally supported adjacent said stop member and adapted for attachment to the hood wall, a resilient strip fixed to said fastening device and lying parallel to the axis of the fastening device, and a buffer carried by said strip and adapted to be compressed between the hood wall and fastening device.
- 20 4. In a hood fastener wherein a hood wall is adapted to be clamped down and against a stop member, a fastening device pivotally supported adjacent said stop member and adapted for attachment to the hood wall, a strip fixed to said fastening device, and a buffer carried by said strip and adapted to be compressed between the hood wall and fastening device.

In testimony whereof I affix my signature.

NORMAN W. CUMMINS.
